UNITED STATES PATENT OFFICE

HENRY MILLER, OF NEWARK, NEW JERSEY, ASSIGNOR TO W. C. EDGE JEWELRY CO.,
OF NEWARK, NEW JERSEY, A CORPORATION OF NEW JERSEY

DESIGN FOR A METALLIC FABRIC FOR JEWELRY

Application filed December 7, 1928. Serial No. 29,151. Term of patent 7 years.

To all whom it may concern:

Be it known that I, HENRY MILLER, a citizen of the United States, residing at Newark, in the county of Essex and State of New Jersey, have invented a new, original, and ornamental Design for Metallic Fabric for Jewelry, of which the following is a specification, reference being had to the accompanying drawing, forming part thereof.

In said drawings, Fig. 1 is a plan or obverse face view of a metallic fabric for jewelry, showing my new design; Fig. 2 is a transverse section thereof on an enlarged

scale taken on the line 2—2 in Figure 1; and Fig. 3 is a fragmentary longitudinal section thereof, also on an enlarged scale taken on the line 3—3 in Figure 1. The design is characterized by the possession of a symmetrically corrugated central longitudinal body, the corrugations extending transversely between relatively flat marginal edge portions.

I claim:

The ornamental design for metallic fabric for jewelry as shown and described.

Dated this 5th day of December, 1928.

HENRY MILLER.
